CLAIM

The ornamental design for a combined marker light and turn signal indicator, as shown and described.

DESCRIPTION

FIG. 1 is an isometric view of a combined marker light and turn signal indicator, showing an embodiment of our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is an isometric view of a combined marker light and turn signal indicator, showing another embodiment of our new design, which is a mirror image of the combined marker light and turn signal indicator shown in FIGS. 1-7.

FIG. 9 is a front elevational view thereof.

FIG. 10 is a rear elevational view thereof.

FIG. 11 is a right side elevational view thereof.

FIG. 12 is a left side elevational view thereof.

FIG. 13 is a top plan view thereof; and,

FIG. 14 is a bottom plan view thereof.

Stippling in the drawings represents the three-dimensional contours of the design, and is not intended to indicate surface decoration. The broken lines shown in the drawings depict portions of the combined marker light and turn signal indicator that form no part of the claimed design.
